H. W. Charlton,
ATTORNEY

UNITED STATES PATENT OFFICE.

JOHN STUART PEARCE, OF VANCOUVER, BRITISH COLUMBIA, CANADA.

PROCESS AND APPARATUS FOR PRODUCING CHARCOAL AND LIKE MATERIALS.

1,395,866.

Specification of Letters Patent. Patented Nov. 1, 1921.

Application filed March 31, 1919. Serial No. 286,549.

To all whom it may concern:

Be it known that I, JOHN STUART PEARCE, a citizen of Canada, residing at Vancouver, in the county of New Westminster and Province of British Columbia, Canada, have invented new and useful Improvements in Processes and Apparatus for Producing Charcoal and like Materials, and has for its object the introduction of a more economical and efficient method than those heretofore proposed.

This invention relates particularly to a new method of carrying out the destructive distillation of waste wood, etc., and producing a very high grade of charcoal, etc., at a minimum cost.

The object of this invention is to provide a method that will be simple in its nature, comparatively easy to carry out and less costly to operate than those at present known. With these and other objects in view the invention consists in the novel steps and combination of steps constituting the process, and the new form of apparatus, all as will be more fully hereinafter disclosed and particularly pointed out in the claims.

The drawing shows a vertical cross section through the apparatus.

A is the part of the furnace in which the fuel is consumed, and the hot combustion gases formed. B is the fuel chamber. C is the fuel bed. H is a gas burner situated in a separate chamber above B. J is a mass of refractory material, such as broken magnesite brick, etc. U is an arched wall at the rear of the fire-box. V is the arch over the fire-box. P are passages or flues connecting the fire-box B with the chamber holding the material J. D is the main flue carrying the hot combustion gases from C and J. W is the bridge for retaining the refractory material J. O is a by-pass flue for diverting the combustion gases from their course through the charcoal chamber during filling and emptying of the latter. S is honey-combed brick work at the end of the flue D. L is the destructive distillation and charcoal forming chamber. X is a discharge door at the bottom of the chamber L through which the charcoal may be removed. R is a car for transporting the charcoal. M are charging tubes. T are doors leading from the exterior to the charging tubes. N

is the exhaust flue leading from the charcoal chamber. K² is a damper in the flue N. K¹ is a damper in the by-pass flue O. K is a damper in the main flue D. Y are small flues leading from the charging tubes to the flue N.

It is preferable to operate both the upper and the lower fuel chambers but it is the upper one that gives the oxygen-free combustion products. Of course if damper K is closed and the gases from the lower grate pass through P the result is the same with the additional advantage that the volume of the gaseous products of combustion is greatly augmented and superheated if desired.

The remarkable activity or catalytic power of incandescent refractory material is well known and it brings about combustion in cases where the proportion of combustible and non-combustible gases is such that they would not ordinarily combine. Although combustible gases and air reacting in presence of this material give out exactly the same amount of heat that they would under any other circumstances, yet the heat is conserved in a limited area and is not dissipated as would otherwise be the case. In addition the combustion is hastened and rendered more complete.

The fuel selected, such as coke, anthracite coal, charcoal, etc., must give off little or no combustible gases while burning, as would be the case were soft coal employed. Otherwise there would be a deposition of carbon, etc., that might choke up the flues. It would also deposit upon and more or less change the nature of the charcoal resulting from the wood treatment. Many of the combustible volatile products from soft coal are much less volatile than those escaping during the destructive distillation of wood. Consequently these would deposit upon the charcoal and decrease its value for metallurgical or other purposes. It might mean that sulfur and like objectionable compounds would be thus introduced into the charcoal and thus add to it elements whose absence is its greatest value.

There is an additional objection to the employment of soft coal. Although in this instance the furnace alone is shown and claimed, yet there is another and equally

important part of the entire process. That is the recovery and the separation of the wood distillation products, which are of great commercial value. The following 5 shows their relative nature and proportions.

	Per cent.
1. Non-condensable gases	20-30
2. Aqueous distillate, (pyroligneous acid)	30-50
10 3. Turpentine, wood oils and wood tar	5-20
4. Charcoal	20-45

At 150° C. the decomposition of the wood commences and is complete at 430° C.

15 There is an absolute difference between the chemical products resulting from a wood and a soft coal destructive distillation. If they were intermingled as would be the case if soft coal were employed in producing the 20 hot combustion gases, the distillation product would be an almost valueless mixture of unknown and uncertain composition.

The fuel, preferably coke or charcoal, is charged into the firebox B through the door 25 F. It rests upon a grate set at an angle of perhaps 45 degrees in front, and through this the cold air entering at E passes horizontally into and through the coal and passes into the flue at the rear. When oxygen-free combustion gases are employed the 30 damper K is closed and all the gases pass through the refractory material J. U is the back wall of the fire-box, and has an arch in the center of the lower portion so that 35 the solid fuel may flow and find its own boundary, through which the heated products of combustion may escape. By closing the damper K the direction of the combustion 40 gases is entirely changed, and they move upward through the flues P and are heated by the incandescent mass J. Below the incandescent material J is situated the burner of any type partially shown at H to raise 45 it to a sufficient temperature to reduce catalytic action.

The size of the burner employed is dependent entirely upon the amount of refractory material. It may be of any type, but must be of such a size that it can 50 alone maintain the refractory material in a state of incandescence, although normally only a part of this heat is required of the burner, the remainder being furnished by the combustion of the fuel in the lower 55 hearth.

The destructive distillation of the waste wood takes place in the chamber L. It is introduced through the doors or covers T into the charging tubes M which also act 60 as preheaters. Being surrounded by an air space the hot gases surround them, and the flues Y also allow a portion of the heated gases to flow through the waste wood in M and into the flue N.

65 From the chamber L the gases are drawn

into the flue N and from there into the condensers, not shown in this application, for collecting the products of distillation.

A very important feature of this device though not shown as it may be of any standard type, is the apparatus for producing a suction. Apparatus of this nature, such as a fan, etc., is so well known and of such common occurrence that it has not been shown in the drawing. Its function is to 70 cause a current of air to enter at E and the gaseous products to be removed at N. The exhaustion apparatus is connected with the exhaust pipe N, but is not shown in the drawing.

The three dampers K K¹ K² are intended to regulate the movements of the gaseous currents. If the chamber L is to be cut off as in discharging the charcoal and filling 80 with wood waste K and K² are closed.

Although it is not shown in the drawing and is not claimed in this application, the gas employed in the burner H is one of wood destructive distillation. It is always advisable to scrub the gas and remove the 90 carbon dioxide before attempting to burn it, but in this case its complete removal is not so essential as the incandescent refractory material aids the combustion.

The present application is intended to 95 show and does show the particular advantages resulting from the direct action of the hot products of combustion upon the wood. In this way the yield is greater than could possibly result from any system of indirect 100 heating, and the gases that are introduced are of material aid in carrying off the products of distillation.

Although in this application I have placed 105 particular stress upon the treatment of wood, I do not wish to be limited in this respect as both my process and apparatus may be employed in the treatment of coal, lignite or shale.

A particular feature of this invention is 110 the partial or complete superheating of the products of combustion and the complete removal of free oxygen which makes it possible to speed up the reaction or regulate it in any way desired.

115 Among the various advantages that my process possesses over those already known, I have discovered after exhaustive research that I am enabled to regulate very accurately the heat to which the wood is subjected in 120 various stages of the process. This makes it possible for me to meet the requirements in relation to three factors of great importance, *i. e.*, 1st., the quality of the by-products, 2nd., the quality of the charcoal, 125 3rd., the speed of the reaction.

To obtain the best results it is necessary to expel the adhering moisture, as well as that formed by the chemical decomposition just prior to the beginning of the exothermic 130

reaction, as quickly as possible. By means of my incandescent refractory material and my separate solid fuel and gas heating device I can accomplish this with ease. Later 5 when the exothermic reaction is going on I control the heat in a way that produces a very high yield of volatile products that are of very considerable value. After this stage is passed the temperature is raised rapidly 10 and the charcoal finished at a much higher heat than would be possible in ordinary processes. This has the effect of producing a remarkably high grade of charcoal, and one that may advantageously replace coal 15 and coke as powdered fuel for metallurgical purposes.

Referring now to the best mode of operation, I may say that at first the solid fuel chamber is made to supply the bulk of the 20 heat, and the gas is simply used to keep the refractory material hot. At this stage at least two thirds of the heat is supplied by the solid fuel. In the second or intermediate stage the heat may be supplied by 25 either the solid or gaseous fuel. In the later stage two thirds of the heat is supplied by the gas. It is this stage that is of particular importance in determining the value of the charcoal, and this particular improvement 30 constitutes a very important feature of my invention. By quickly raising the temperature in the last stage and finishing the charcoal at a very high temperature I obtain a very superior product, and one 35 eminently fitted for metallurgical work, and especially adapted for burning as powdered fuel. My invention thus comprises not only a new method of producing charcoal but in reality a new type or quality of 40 charcoal.

It is obvious that those skilled in the art may vary the form of apparatus as well as the details of the process without in any way departing from the spirit of the invention. Therefore I do not wish to be limited 45 to the above disclosures except as may be required by the claims.

I claim:—

1. A method of destructive distillation 50 which comprises bringing gaseous products of combustion into intimate contact with a mass of independently heated refractory material, designed to act as a catalyst, and then through a mass of wood waste; substantially 55 as described.

2. A method of destructive distillation which comprises passing the products of combustion of solid fuel through a mass of refractory material in contact with which 60 heated gaseous fuel is being burned, and leading the combined products of combustion through a mass of wood; substantially as described.

3. A method of destructive distillation

which comprises passing products of combustion heated to a temperature slightly below that at which they pass from the fuel, and mixed with other products of combustion superheated in passing through incandescent refractory material, in contact with 70 a mass of wood, and removing the volatile products of decomposition associated with the originally introduced products of combustion; substantially as described. 65

4. In an apparatus for destructive distillation, a combustion chamber divided into two parts, one part adapted to consume solid fuel and the other part adapted to consume gaseous fuel, a mass of refractory material in the gaseous fuel section, a flue leading 75 from the fuel chamber to the charcoal forming chamber, a charcoal forming chamber with a discharge flue adapted to remove the gases, and a discharge door adapted to remove the charcoal; substantially as described. 80

5. In an apparatus for destructive distillation, a combustion chamber divided into two parts, the upper one being adapted to consume gaseous fuel, and the lower one being adapted to consume solid fuel, a flue 90 connecting the lower and the upper sections of the fuel chamber, a mass of refractory material in the upper section of the fuel chamber, a common flue leading from the two sections of the fuel chamber to the charcoal forming chamber, a charcoal forming chamber with a discharge flue adapted to remove the gases, and a discharge door adapted to remove the finished charcoal; substantially as described. 95

6. In an apparatus for destructive distillation, a combustion chamber divided into two parts, the upper one being adapted to consume gaseous fuel, and the lower one adapted to consume solid fuel, a flue connecting the lower and the upper sections of the fuel chamber, a mass of refractory material in the upper section of the fuel chamber, a common flue leading from the two sections of the fuel chamber with a damper 105 adapted to shut off the lower section of the fuel chamber, the said flue leading into the charcoal forming chamber, a charcoal forming chamber, charging chambers in the upper portion of the charcoal forming chamber and surrounding the flue adapted to carry off the escaping gases, lattice work 110 in the lower portion of the charcoal forming chamber and adapted to support the mass of wood, an outlet in the bottom of the charcoal forming chamber adapted to discharge the finished charcoal; substantially 115 as described. 120
